UNITED STATES PATENT OFFICE

IRVEN H. WILSEY, OF CHICAGO, ILLINOIS

ROTARY MACHINE

Application filed November 30, 1927. Serial No. 236,661.

The present invention relates to improvements in rotary machines, and particularly rotary gear pumps of the type disclosed in my copending application, Serial No. 204, 5 467, filed July 9, 1927.

The primary object of the present invention resides in the provision in a rotary machine adapted to handle fluids of a new and improved packing which will prevent objectionable leakage and which will not deteriorate appreciably through action of the fluid.

In ordinary rotary machines, such as rotary gear pumps adapted to handle fluids under relatively high pressures, leakage may occur 15 along the drive shaft. This of course is objectionable, and particularly so where the fluid is an acid or corrosive oil, such as fuel oil. Heretofore, various types of packings, including seal ring packings with lapped 20 bearing surfaces, have been provided to correct this difficulty. Packing relying on lapped bearing surfaces for an effective fluid seal may operate satisfactorily for a while, but in a relatively short time, if corrosive fluids under high pressures are being handled, some 25 fluid will work between these surfaces and corrode them, thereby destroying the seal. An important object of the present invention therefore resides in the provision of novel 30 means for venting the packing to the low pressure side of the machine, thereby maintaining a relatively low pressure at the packing.

A further object resides in the provision in 35 a rotary gear pump of a new and improved fluid seal which will vent automatically to the suction side of the pump regardless of the direction of rotation of the pump.

Another object is to provide a seal ring 40 packing in which the pressures acting on the seal ring are maintained substantially in balanced relation.

A further object resides in the provision in 45 a seal ring packing of the above character of means for preventing the passage of fluid between the bearing surfaces through capillary action.

Further objects and advantages will 50 become apparent as the description proceeds.

In the accompanying drawings, Figure 1 is

a side elevation of a pump embodying the features of my invention.

Fig. 2 is a longitudinal vertical sectional view of the pump.

Fig. 3 is a sectional view taken along line 55 3—3 of Fig. 2.

Fig. 4 is an end view of the venting collar.

Fig. 5 is a sectional view taken along line 5—5 of Fig. 4.

Fig. 6 is a fragmentary sectional view of a 60 modified form of packing.

Fig. 7 is a longitudinal vertical sectional view similar to Fig. 2 but showing another modified form of packing.

Fig. 8 is a sectional view taken along line 65 8—8 of Fig. 7.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope 70 75 of the invention as expressed in the appended claims.

The exemplary embodiment of the invention is shown incorporated in a single stage rotary gear and pinion pump, but it is to be understood that it may be used in a large variety of pumps and rotary machines. In the present instance, the pump comprises a suitable casing 10 which preferably is cylindrical in shape, and which is formed with a cylindrical chamber 11 open at one end. Of the casing 10, the open end is closed by a removable cover plate 12 secured thereto by any suitable means, such as a plurality of screw bolts 13, and the other end is formed with a central bearing 14 having a bore 15 opening to the inner end of the chamber 11. Suitable inlet and discharge passages 16 and 17 open respectively to opposite sides of the chamber 11, and preferably are formed in fittings 18 and 19 integral with the casing 10.

Rotatably mounted in the cylindrical chamber 11 is a rotor 20 which is provided with a drive shaft 21 adapted to be connected to a suitable source of power (not shown).

The rotor 20 preferably comprises a circular plate which bears against the inner end of the chamber 11, and which has a close peripheral bearing contact with the inner peripheral surface of the chamber. Formed on the front 5 end of the rotor 20 are a plurality of laterally projecting and peripherally spaced internal gear teeth or vanes 22. These teeth are concentric with respect to the shaft 21, and 10 mesh with a pinion 23 eccentrically related thereto. Preferably, the pinion 23 is mounted on a pin 24 journaled in a suitable bearing 25 in the cover plate 12. A crescent partition 26 is disposed between the rotor vanes 22 and the pinion 23. In operation, if the shaft 21 15 is rotated counter-clockwise, as viewed in Fig. 3, fluid will enter through the suction passage 16 to fill the interdental spaces between the teeth of the rotor 20 and the pinion 23 at the suction side of the partition 26, will then be carried past the partition 26 into the discharge side of the pump, and from there will be discharged through the passage 17. Obviously, if the rotation of the 20 shaft 21 is reversed, the passage 17 will be the inlet passage and the passage 16 will be the discharge passage.

Considerable difficulty is ordinarily encountered in preventing leakage from the 25 chamber 11 past the rotor bearing surfaces and along the shaft 21 through the bearing 14. This is particularly so when corrosive fluids such as acid fuel oil are handled which in a short time, pit and corrode the bearing 30 surfaces, thereby resulting in leakage. The present invention contemplates the provision 35 of a new and improved packing for the shaft 21 which will prevent leakage, and which will not deteriorate appreciably over a substantial period of time through any action 40 of the fuel oil or other fluid passing through the pump.

The packing comprises a bushing 27 fixed 45 in the outer end of the bore 15, and providing a rigid bearing for the shaft 21. The inner end of the bore 15, between the rotor 20 and bushing 27 is slightly enlarged in diameter 50 to form a chamber 28. Disposed on the shaft 21 is a seal ring 29 which is connected 55 through a suitable flexible diaphragm 30, to the rotor 20. In the present instance, the ends of the diaphragm 30 are soldered respectively to the rotor shaft 21 and the seal 60 ring 29 near its outer periphery, thereby defining a fluid tight chamber 31 normally filled with a heavy lubricant. Preferably the diaphragm 30 is made of resilient material. The outer end of the seal ring 29 is 65 provided with a lapped bearing surface 32 which is adapted to bear against another fixed lapped surface as hereinafter described. It will be evident that in the construction 70 thus far described, the pressure in the chamber 31 will be atmospheric, and the pressure 75 in the chamber 28 would be that of the dis-

charge passage 17 if no vent were provided. This pressure difference would tend to force fluid between the lapped sealing surfaces which would soon destroy the effectiveness of the latter.

Means is provided for venting the chamber 28 to the suction side of the pump. To this 80 end, two vent passages 33 and 34 are formed in the casing 10, and connect the passages 16 and 17 to opposite sides of the chamber 28. Preferably, the passages 33 and 34 open at 85 diametrically opposed points in the inner end of the bushing 27, and are adapted to be closed selectively by a venting collar 35. The venting collar 35 is rotatably disposed on the shaft 21 between the inner end of the bushing 27 and the outer end of the seal ring 29, and its opposite ends are lapped to provide sealing surfaces 36 and 37 bearing respectively against the lapped surface 32 of 90 the seal ring and the inner lapped end surface 38 of the bushing 27. Formed in the periphery of the collar 35 is an arcuate notch 39 which receives a pin 40 projecting from the end of the bushing 27. The pin and notch 95 connection between the bushing 27 and the venting collar 35 permits a limited rotational movement of the latter through frictional drag with the seal ring and the shaft 21 upon reversal of rotation of the latter. The collar 100 35 is formed with two spaced ports 41 and 42 opening therethrough, and arranged for movement into selective registration with the passages 33 and 34 upon rotation of the collar 105 35 into either of its extreme positions. It 110 will be evident that by means of this construction the chamber 28 will be vented automatically to the suction side of the pump regardless of the direction of rotation of the shaft 21, thereby maintaining a relatively 115 low pressure therein, and that as a result the fluid leaking from the chamber 11 will not enter between the lapped sealing surfaces.

To provide a balance for the seal ring 29, the outer end is provided with a deep annular notch 43 providing an annular space between the ring and the collar 35 to which the ports 41 and 42 open. By this construction, the surface 32 is maintained close to the shaft 21, and the pressure on the exposed part of the ring is opposed to the pressure in the chamber 31.

In some instances, where the fluid in the chamber 31 is heavier than the fluid in the chamber 28, to prevent a tendency of capillary action to carry fluid past the lapped surfaces, I have provided a seal ring 44 (see Fig. 6) having beveled edges 45 and 46 at opposite sides of the lapped surface. These beveled edges may be inclined at different 120 angles for fluids having different viscosities.

In Figures 7 and 8 I have shown a modified form of the invention in which the automatic venting collar is omitted. In this form 125 passages 47 and 48 directly connect the pas- 130

sages 16 and 17 respectively to the chamber 28. The outer end of each passage is screw-threaded, and is adapted to receive a screw plug 49. In use, the passage 47 or 48 opening to the high pressure side of the pump is closed by the plug 49.

Referring to Figs. 1 to 6, instead of having the passages 33 and 34 opening in the end of the bushing 27, they may open in the peripheral wall of the chamber 28. In this event, the venting collar 35 should have a peripheral contact with the inner peripheral wall of the chamber 28 so as to selectively close one or the other of the passages 15 in the same manner as described in the foregoing.

I claim as my invention:

1. A rotary machine having, in combination, a casing having relatively high and low pressure spaces, a fluid handling mechanism in said casing, said mechanism comprising a rotary element, an operating shaft for said rotary element, a seal ring mounted on said shaft, said seal ring and a portion of said casing having coacting lapped surfaces, a flexible diaphragm connecting said seal ring to said rotary element, and means for venting the space about said seal ring and said surfaces to said low pressure space.

2. A rotary machine having, in combination, a casing having relatively high and low pressure spaces, a fluid handling mechanism in said casing, said mechanism comprising a rotary element, an operating shaft for said rotary element, a seal ring mounted on said shaft, a flexible diaphragm connecting said seal ring to said rotary element, a pair of passages extending from the space about said seal ring respectively to said spaces, and a collar 40 having a limited rotary movement on said shaft and adapted to close said passages selectively upon angular movement into its extreme positions, said ring, said collar and said casing having coacting lapped surfaces.

3. A rotary machine having, in combination, a casing having an inlet passage and a discharge passage, a gear rotor in said casing, a pinion eccentrically related to said rotor and meshing therewith, a partition 50 located between said rotor and said pinion, a shaft for driving one of said gear elements, a bushing on said shaft, a seal ring on said shaft having a lapped surface on one end, a flexible member effecting a fluid tight connection between the other end of said seal ring and said

55 shaft, a venting collar disposed between said ring and said bushing, said collar having a lapped surface coating with said first mentioned surface and having a relatively limited rotary movement, a pair of venting passages leading respectively from said inlet and discharge passages to said venting collar, and a pair of ports in said collar adapted to 60 be moved selectively into registration with

the openings of said venting passages, and opening to the space about said ring.

4. A rotary machine having, in combination, a casing having relatively high and low pressure spaces, a fluid handling mechanism 70 in said casing, said mechanism comprising a rotary element, an operating shaft for said rotary element, a seal ring mounted on said shaft, a diaphragm connecting said seal ring to said rotary element, a member on said shaft, said ring and said member having coacting bearing surfaces, and means for venting the space about said ring automatically to the low pressure space regardless of the direction of rotation of said shaft.

5. A rotary machine having, in combination, a casing having relatively high and low pressure spaces, a fluid handling mechanism 80 in said casing, said mechanism comprising a rotary element, an operating shaft for said rotary element, a bushing for said shaft, a seal ring mounted on said shaft, fluid tight means connecting one end of said seal ring to said rotary element, a collar bearing between said bushing and said shaft, and means controlled by said collar for venting the space about said ring to said low pressure space.

6. A rotary machine having, in combination, a casing having relatively high and low pressure spaces, a fluid handling mechanism 90 in said casing, said mechanism comprising a rotary element, an operating shaft for said rotary element, a seal ring mounted on said shaft, fluid tight means connecting said seal ring to said rotary element, and a member 100 bearing against said seal ring, the inner edge of the bearing surface of said ring being beveled.

7. A rotary machine having, in combination, a casing having an inlet passage and a discharge passage, a gear rotor in said casing, a pinion eccentrically related to said rotor and meshing therewith, a partition located between said rotor and said pinion, a shaft for driving one of said gear elements, a bushing 110 for said shaft, a seal ring on said shaft having a lapped surface on one end, a flexible member effecting a fluid tight connection between the other end of said seal ring and said shaft, a venting collar disposed between said ring and said bushing, said collar having a lapped surface coating with said first mentioned surface and having a relatively limited rotary movement, means controlled by the position of said collar for venting the space 120 about said ring to said inlet passage, said ring having a peripheral notch in the end having the lapped surface.

8. A rotary machine having, in combination, a casing having relatively high and 125 low pressure spaces, a fluid handling mechanism in said casing, said mechanism comprising a rotary element, and an operating shaft for said rotary element, the pressure in said spaces being interchangeable by re- 130

versal of said rotary element, coacting sealing members, one having a fluid tight connection with said casing, and another having a fluid tight connection with said shaft, 5 one of said connections being yieldable, and means automatically operable to vent the space at one side of said yieldable connection to the low pressure space regardless of the direction of rotation of said rotary element.

10 9. A rotary machine having, in combination, a casing having relatively high and low pressure spaces, a fluid handling mechanism in said casing, said mechanism comprising a rotary element, and a shaft for said element, said casing being formed with two vent passages, one leading from each of said spaces and terminating in a port opening to the space about said shaft, a 15 shiftable member having two openings adapted to be moved alternately into and out of communication with said ports respectively upon movement of said shiftable member in opposite directions, and means for shifting said shiftable member upon reversal of rotation of said shaft.

10 10. A rotary machine having, in combination, a casing having two separate spaces, fluid handling mechanism in said casing, 30 said mechanism comprising a rotary element, and a shaft for said element, said casing having two vent passages, one leading from each of said spaces and terminating in a port opening to the space about said shaft, 35 a rotatable member positioned over said ports and having two openings adapted to be moved alternately into and out of communication with said ports respectively upon rotation of said member in opposite directions, and means for rotating said member upon reversal of rotation of said shaft.

11. A rotary machine having, in combination, a casing, relatively reversible high and low pressure spaces, fluid handling mechanism in said casing, said mechanism comprising a rotary element, two vent passages leading respectively from said spaces and terminating in ports opening to the space about said element, a rotatable member overlying said ports and having two openings adapted to be moved alternately into and out of communication with said ports respectively upon movement of said member in opposite directions, means for limiting the 50 movement of said member and means for rotating said member upon reversal of rotation of said element.

In testimony whereof, I have hereunto affixed my signature.
